[57] CLAIM

The ornamental design for a disposable urinal holder, as shown and described.

DESCRIPTION

FIG. 1 is a right side elevational view of a disposable urinal holder embodying my new design, with a left side elevation thereof being a mirror image thereof;

FIG. 2 is a front elevational view thereof;

FIG. 3 is a top plan view thereof;

FIG. 4 is a bottom plan view thereof; and

FIG. 5 is a rear elevational view thereof.
